UNITED STATES PATENT OFFICE.

ANDREW L. RIKER, OF SHORTHILLS, NEW JERSEY, ASSIGNOR, BY MESNE ASSIGNMENTS, TO MORTON TRUST COMPANY, TRUSTEE, A CORPORATION OF NEW YORK.

DESIGN FOR A VEHICLE-BODY.

SPECIFICATION forming part of Design No. 36,225, dated February 10, 1903.

Application filed March 28, 1901. Serial No. 53,360. Term of patent 14 years.

To all whom it may concern:

Be it known that I, ANDREW L. RIKER, a citizen of the United States, and a resident of Shorthills, in the county of Essex and State of New Jersey, have invented and produced a certain new, original, and ornamental Design for Vehicle-Bodies, of which the following is a specification, reference being had to the drawings accompanying and forming a part hereof.

This invention relates to automobile-bodies, or more particularly to such bodies for motor road-vehicles; and it consists in a design for such, as shown in the accompanying drawings, in which—

Figure 1 is a perspective view from the side and a little forward of the middle of the vehicle, while Fig. 2 is a perspective view from the forward end and a little to one side.

The essential features of my design are the body portion, generally resembling the well-known hansom-lines, with an operator's seat in the rear and a downwardly-projecting portion below the floor of the body and a relatively small box portion contiguous with the toe of the base portion, which lower portion appears prominent and large in aspect relatively in proportion to the main body portion or to the hood portion, in a measure dominat-

ing the design, or in its appearance attracting attention of the casual observer.

A is the main body portion, consisting of the hood *a* and the seat portion *b*, merging into the floor portion *c*.

B is the operator's seat, rearwardly extending from the hood portion and at a high level.

Below the floor portion or merging into the floor outlines is the substantially rectangular deep subfloor portion *C*, harmonizing in outline with the rest of the body and in appearance presenting a substantial lower part which to the observer gives the impression of balancing the large upper hood portion.

At *D* is indicated an extension from the toe of the floor, which may, however, vary considerably in form and precise position without affecting the appearance of my design due to the essential features.

I claim as my invention—

The ornamental design for a vehicle-body substantially as shown and described.

This specification signed and witnessed this 12th day of February, A. D. 1901.

ANDREW L. RIKER.

In presence of—

WM. H. BARKER,
HERMANN F. CUNTZ.
